UNITED STATES PATENT OFFICE

2,506,328

PLASTIC FIGURINE

Don L. Alger, Avalon, Calif.

Application March 24, 1947, Serial No. 736,808

6 Claims. (Cl. 46—173)

1

This invention relates to new and useful improvements in amusement devices.

The objects of this invention are to provide an amusing and educational novelty device; to provide figurines of various configurations simulating a variety of subjects; to provide novel means for securing elements of said figurines in certain adjustable predetermined relation; to provide means to adjustably and removably connect various elements of the figurines simulating clothing; to provide gay colored components offering selective choice of colors thereof; to provide an inexpensive assembly of elements conducive of entertainment.

Ancillary objects and features of novelty will become apparent to those skilled in the art, in following the description of the illustrated preferred embodiment of the present invention depicted in the accompanying drawings, wherein:

Figures 1 and 2 are pictorial views of an assembled embodiment of the present invention;

Figure 3 is a perspective fragmentary detail view showing a clamping means for joining the arm to the shoulder;

Figure 4 is a perspective fragmentary detail view showing the clamping means used to join the hand to the arm;

Figure 5 shows a second embodiment of the instant invention in exploded form;

Figure 6 shows a third embodiment of the instant invention, showing the same in exploded form;

Figure 7 shows a fourth embodiment of the instant invention, illustrating an alternate friction securing means to be used between the lower and upper anatomy portions;

Figure 8 is a fragmentary upper anatomy portion of the said fourth embodiment, showing specifically an alternate friction securing means to be used between the head and shoulder portion;

Figure 9 is a perspective view of a button to be used in each of the first four embodiments of the present invention;

Figure 10 is a perspective view of a pair of suspenders to be used in conjunction with the illustrated first four embodiments of the instant invention;

Figure 10a is a fragmentary perspective view of the block keeper used in conjunction with the securing means for the above mentioned button and for the suspenders.

Referring now in detail to the illustrated preferred embodiments of the instant invention, like reference characters are used throughout to indicate similar elements.

2

This invention relates to a novel and improved pleasure conducive device which is both entertaining and educational. The broad operation of the invention resides in the assembly and dismantling of components to construct figurines. The preferred material of construction is commercial plastic, however other material may be used if so desired. This invention contemplates the use of fancifully painted wood components, light metal components and the like.

Referring now to the first four embodiments of the present invention, which are very closely allied, it is noted that a body portion 10 and a lower anatomy portion 12 are provided. It is clearly seen that the body portion 10 simulates the chest and shoulder members of a human being. It is further readily apparent that the lower anatomy portion 12 simulates the legs and torso of a person. It is well to note at this point, that the basic components of the figurines disclosed in the first four embodiments of the present invention, are similar differentiating only in the securing means used therewith. Obviously, the particular shape of the nose, chin and fingers, etc. of a man have no bearing on the invention.

Taking now the embodiment of Figure 5, it is noted that an arm 14 is removably and adjustably secured to the said body member 10. For this purpose a plurality of lugs 16 are provided at the upper terminal portion of the said arm. Complemental apertures 18 are provided in the shoulder portion of the said body member to receive said lugs. It is readily apparent that the arm 14 is frictionally received on the said body member 10 through the medium of the said lugs and apertures.

A hand portion 20 is provided with a pair of lugs 22 projecting therefrom which are adapted to be received in selected adjustable frictional engagement with the wrist portion of the said arm 14.

A foot portion, in the form of a boot, is generally designated by the numeral 24 and is provided with a plurality of apertures 26 at the upper portion thereof. Lugs 28 depend from the said lower anatomy portion 12 and are adapted to be engaged in frictional relation with the confines of the apertures 26.

A head portion 30 has a peg 32 extending from the neck thereof. It is apparent from an inspection of Figure 5, that the said peg 32 is adapted to be adjustably and frictionally engaged within the confines of the aperture 34 provided in the appropriate place in said body member 10. A

member 36 simulating hair has secured thereto a plurality of pins 38 which are adapted to be received in suitable apertures 40 provided on the substantially bald head member 30. A hat 42 may be rested on the head portion or hair member if so desired.

A plurality of buttons 44 are secured to the chest portion of the said body member 10. Reference to Figure 9 discloses the preferred construction of said buttons. Further, reference to Figure 10^a discloses the preferred keeper to be used as a part of the securing means for said button. It is noted that a right angular latch 46 is rigidly secured to the back portion of the button 44. Provided in the said chest portion 10 is a plurality of slots 48 adapted to receive the said latch 46 therein. It is apparent that the buttons 44 may be inserted in the chest portion of the figurine, turned a portion of a revolution and thereby held securely thereto.

A plurality of lugs 50 are provided at the lower portion of the said body member 10 and are adapted to be received in complementary bores 52 provided in the upper portion of the said lower anatomy 12. Received exterior of the said lugs and apertures 50 and 52 respectively, is a belt 54 adapted to encircle the waist portion of the said figurine. A simulated buckle 56 is formed integral with the belt 54 and a tongue 58 projects from the inner surface of the belt adjacent the said buckle 56. A suitable slot 60 is provided through the portion of the belt at the opposite end from the said buckle 56. Obviously, this tongue 58 is adapted to go through the said slot 60 thence through a suitable, similar slot 62 in the waist portion of the figurine. It is apparent that the belt 54 will be held securely about the waist of the figurine by this construction. It is here noted that a plurality of slots 48 are provided adjacent the said slot 62. The said slots 48 have been described hereinabove.

Reference is now made to the embodiment of the invention disclosed in Figure 6. The back and chest portion 10 is provided with a different type of shirt thereon. The torso portion 12 is identical to the above described member 12 with the exception of the friction securing means. A plurality of slots 64 are provided about the upper portion of the torso member and are adapted to be used in conjunction with the keepers 66 to be described at this time. Depending from the said body member 10 is a plurality of generally rectangular keepers 66 adapted to be frictionally engaged within the confines of the said slots 64. Obviously, this construction permits a relatively rotatable adjustment between the said body and torso members.

The arms 14 are provided with a single peg 68 integral with the upper portion thereof. A right angular lug 70 is provided on the said peg 68 to complete the latch mechanism. An aperture 72 is provided at the shoulder portion of the said body member and a suitable slot 74 is provided in the periphery thereof. It is quite apparent that the arm 14 is adapted to be secured to the said body through the medium of the above described structure. The peg 68 is inserted in said aperture, then turned thereby binding the said lug 70 therebehind. This construction permits a swinging adjustment of the said arm 14.

The head portion 30 is provided with a plurality of lugs 76 adapted to be received in selected apertures 78 provided in the said body member 10 adjacent the neck portion thereof.

A pair of sockets 80 are provided in the said head portion and slots 82 communicate therewith.

The said sockets and slots are adapted to receive removably therein eye members to be described at this time. An eye ball 84 is provided with a single lug 86 adapted to be received in the said slot 82. Obviously, the eye ball 84 will then be received in the socket 80. A suitable threaded aperture 88 is provided in the front portion of the eye ball and a screw threaded iris 90 is received in said aperture 88. It is here noted that this eye construction may be used in each of the first four embodiments of the present invention. For convenience of illustration the eye member has been disclosed as removable only in the embodiment shown in Figure 6. A suitable hat 92 may be provided on the head portion 30 of the herein described figurine.

A member 94 simulating hair is provided with a pair of legs 96 having arcuate end portions 98 thereon. A lug 100 is provided between said legs 96 and is adapted to be received in a suitable aperture 102 located adjacent the nose of the said figurine. A pair of apertures 104 are provided adjacent the ears for receiving the said arcuate portions 98 thereon. Obviously, by this construction the hair member 94 may be removably secured to the head portion 30 in this embodiment of the instant invention.

Referring now to the embodiment disclosed in Figures 7 and 8, it is noted that the body portion 10 and torso portion 12 are disclosed. Adjacent the waist of the figurine represented by these portions, are screw threaded portions 106 and 108. These threads are complementary and are adapted to retain the member 10 in frictional engagement with the said member 12. By constructing the threads slightly out of pitch, a relatively tight fit may be effected thereby rendering a fixed adjustment between said members possible.

Suitable complementary threads 110 and 112 are provided on the head portion 30 and body member 10 respectively. These threads may also be slightly out of pitch for rendering a stiff friction lock between the said head member and body.

Taking now Figures 1 to 4 inclusive, another embodiment of the present invention will be described. The figurine appearing in Figures 1 and 2 are quite similar to those disclosed in the hereinabove described species. However, a modified form of friction securing means is provided in joining components thereof. By way of example, securing means between the arm and shoulder and hand and wrist are illustrated in detail. A tongue of substantially rectangular configuration is provided at the upper extremity of the arm portion 14 and is generally designated by the numeral 114. A plurality of slots 116 crossing at a common point are provided at the upper extremity or shoulder portion of the said member 14. It is apparent that the arm 14 may be adjustably and frictionally secured in said body member through the medium of the tongue 114 and groove 116.

At the lower extremity of the said arm 14 is a plurality of slots 118 similar to the slots 116. A tongue 120 is provided on the wrist portion of the said hand 20 and is adapted to be selectively engaged within the said slots 118.

A pair of suspenders 122 are provided with a plurality of lugs 124 at the extremity thereof. These lugs are adapted to be received in the hereinabove described slots 48. It is here noted that that the suspenders are adapted to be used in each of the above described modifications of the invention. It is readily apparent from an in-

spection of Figure 10^a that the aperture or slot 48 is provided with a round portion 126 so that it may be universally used both with the suspenders and with the buttons 44. Obviously, the suspenders 122 are adapted to be received over the shoulders of the figurine and are adapted to be secured at the waist portion thereof.

It is here noted that the removable hair, removable eye members (including the removable iris), removable buttons, foot portion, etc. may be used in the figurine disclosed in Figures 1 to 4 inclusive.

Having thus described the instant invention, what is claimed as novel and improved is as follows:

1. A figurine simulating a human being comprising a chest and back member, a lower anatomy portion, friction means for securing said lower anatomy portion to said chest and back member, slots in said lower anatomy portion adapted to receive a belt and suspenders selectively therein, slots in said chest and back member, a plurality of buttons having arms secured thereto adapted to be removably received in said chest and back member slots, friction securing means in said chest and back member for securing arms therein in selected positions relative to said member, hand portions, means for frictionally and adjustably securing said hand portions to said arms, a head portion removably secured to said member, simulated hair removably secured to said head portion, sockets in said head, simulated eye balls, means for removably securing said eye balls in said socket, and a removable iris in each of said eye balls.

2. A figurine comprising a chest and back member, a lower anatomy portion, friction means securing said lower anatomy portion to said chest and back member, slots in said lower anatomy portion receiving selectively in removable engagement therewith a belt and suspenders, slots in said chest and back member, and a plurality of buttons having arms secured thereto disposed in said last mentioned slots removably.

3. A figurine comprising a chest and back member, a lower anatomy portion, friction means securing said lower anatomy portion to said chest and back member, slots in said lower anatomy portion receiving selectively in removable engagement therewith a belt and suspenders, slots in said chest and back member, and a plurality of buttons having arms secured thereto disposed in

said last mentioned slots removably, said chest and back members having a plurality of intersecting shoulder slots, arms having tongues frictionally retained in said last mentioned slots selectively, whereby the arms may be adjusted to various steps of rotational position.

4. A figurine comprising a chest and back member, a lower anatomy portion, friction means securing said lower anatomy portion to said chest and back member, slots in said lower anatomy portion receiving selectively in removable engagement therewith a belt and suspenders, slots in said chest and back member, and a plurality of buttons having arms secured thereto disposed in said last mentioned slots removably, said chest and back members having a plurality of intersecting shoulder slots, arms having tongues frictionally retained in said last mentioned slots selectively, whereby the arms may be adjusted to various steps of rotational position.

5. In a figurine simulating a human being, a chest and member, a lower anatomy portion frictionally and detachably secured to said chest and back portion, arms adjustably secured to said chest and back portion, hand portions detachably secured to the ends of said arms, simulated hair having pegs extending therefrom, a head portion detachably secured to said chest and back portion, said head portion having apertures therein detachably seating said pegs in said simulated hair portion, said chest portion having slots therein, buttons, arms attached to said buttons disposed in said chest portion slots.

6. The combination of claim 5 and said arms which are attached to said buttons being substantially L-shaped, whereby upon rotation of said arms in said chest slots the buttons are maintained firmly in position.

DON L. ALGER.
